UNITED STATES PATENT OFFICE.

WILLIAM H. VOSS, OF DAVENPORT, IOWA,

WASHTUB STAND.

Application filed March 31, 1922. Serial No 548,313.

To all whom it may concern:

Be it known that I, WILLIAM H. Voss, a citizen of the United States, residing at Davenport, Iowa, have invented certain new and useful Improvements in Washtub Stands, of which the following is a specification.

My invention relates more particularly to the construction of portable stands adapted to be folded up when not in use and stored in any convenient place and comprises among its objects to provide such a stand having such a construction that parts thereof can be folded into overlapping positions so as to occupy as little space as possible and yet have the requisite strength and rigidity; to construct a stand of the character stated having provision for carrying away any water draining from tubs mounted thereon; to provide a stand of the character stated having drainage means carried thereby and means connected with the drainage means to prevent the splashing of water being drained from a tub or tubs mounted on the stand; and such further objects, advantages, and capabilities as will later more fully appear.

My invention further resides in the combination, construction, and arrangement of parts illustrated in the accompanying drawings, and while I have shown therein a preferred form of my invention I desire the same to be understood as illustrative only and not as limiting said invention.

35 In the drawings annexed hereto and forming a part hereof,

Fig. 1 is a perspective view of a stand embodying my invention having mounted thereon in position of use one tub.

40 Fig. 2 is a perspective view of my new stand in folded position.

Fig. 3 is a longitudinal vertical section of my new stand with a pair of tubs mounted thereon.

45 Fig. 4 is a plan view of this new stand with the tubs removed therefrom.

Fig. 5 is a cross section through one end of my stand and a tub mounted thereon.

Referring more in detail to the annexed drawings, numeral 1 denotes a pair of side pieces and 2 a plurality of cross pieces secured to the top of the side pieces and together forming a top on which may be supported tubs 3. A drain trough 4 is mounted within the confines of the top and

may be secured to a part or all of the cross pieces 2 in any suitable manner. The manner of securing the trough to these cross pieces is at present considered unimportant, so long as the trough is firmly secured in place in such position that water draining from the tubs will be sure to reach the interior of the trough.

In the form of my invention shown in the accompanying drawings a nipple 6 is provided on the underside of the trough, to which may be secured, as by a close sliding fit, a drain pipe 7 which will carry the water downwardly into a bucket, floor drainage openings, or the like. It will therefore be seen that with such a construction it will be an easy matter to remove the pipe 7 and place the same wherever desired, as, for example, inside of the trough 4, for storage purposes. With the parts so arranged, this part of the construction will be entirely within the confines of the top. The legs 8 and 9 which are pivoted to the top at 10 and 11, can now be folded into overlapping relation with and in close proximity to the underside of the top. It will be clear from the drawings that legs 8 fold inside of the side pieces 1, while legs 9 fold outside thereof. It is also clear that the cross pieces 12 will extend across the underside of the top in such a manner as to serve as protecting means for the drainage trough 4. The cross pieces 2 are shown as provided with a plurality of cleats which serve to properly position the tubs on the stand when in use and to prevent the same from longitudinal motion thereon.

It is of course understood that the specific description of structure set forth above may be departed from without departing from the spirit of my invention as set forth in this specification and the appended claims.

Having now described my invention, I claim:

1. In a stand of the character described, a supporting top, legs pivoted thereto and foldable into a position in close proximity to the top, and a drain trough mounted in said top and adapted to receive drainage from a container resting on the top when in use.

2. In a structure of the character described, a supporting top, legs pivoted thereto and foldable into a position in close proximity to the top, and a drain trough secured

to said top beneath the upper face thereof to receive drainage from removable containers on the top when in position of use.

3. In a structure of the character described, a foldable stand having mounted within the confines thereof a drain trough for receiving water draining from a plurality of tubs on the stand, said stand being provided with means to detachably support and position tubs thereon, in position for the

water draining from the tubs to enter the trough.

In witness whereof, I hereunto subscribe my name to this specification in the presence of two witnesses.

WILLIAM H. VOSS.
